UNITED STATES PATENT OFFICE

ALFRED F. SCHRUP, OF DUBUQUE, IOWA, ASSIGNOR TO H. B. GLOVER COMPANY, OF DUBUQUE, IOWA, A CORPORATION OF IOWA

COMBINED GARMENT AND HOOD

Application filed April 27, 1929. Serial No. 358,459.

My invention relates to wearing apparel and particularly to the type adapted for outer wear during cold weather such as jackets, overcoats, and other over garments.

Garments of the prior art have employed the collar thereof as a hood but these structures have resulted in unsightly collars of peculiar shapes or in hoods which have been unsatisfactory in service, either failing to cover the head completely or covering it so closely as to be uncomfortable. Some of the collars have been of double thickness which, while perhaps satisfactory with light material, with heavier material forms a collar of great thickness which is very cumbersome in normal use.

My invention has for its principal object the provision of a garment having a collar adapted to be used as a hood to protect the neck and head when desired, wherein the fastening means is easily and conveniently operated to form a neat and trim hood and the collar when down presents the usual appearance of a sailor collar.

Other objects and advantages resulting from my invention will become apparent from the following description and the accompanying drawings in which—

Figure 1 is a perspective of a coat embodying my invention showing the collar raised to the hood position, and, in dotted lines, the normal position of the collar;

Fig. 2 is a side elevation of the top of the hood showing the shape of the upper edge thereof;

Fig. 3 is a rear view of the coat showing the collar down and in dotted lines the position of the hookless fastener;

Fig. 4 shows the under side of the lower end of the collar indicating in detail the position and manner of attaching the hookless fastener; and

Fig. 5 is a section on the line 5—5 of Fig. 4.

Referring to Figs. 1 and 3 the garment illustrated will be seen to be of the mackinaw type having a back portion 7, pockets 8 at-

tached thereto, sleeves 9, and front portions 10 and 11.

The coat is of the single breasted type, the left side buttoning over the right. A collar 12 is attached to the coat at the neck band and is permitted to hang down over the back 7, the collar being of sufficient width to extend out over the shoulders in the manner of a sailor collar. The parts of the front portions 10 and 11 which border on the neck of the garment are adapted to be folded outward to provide lapels 13 and 14. The collar extends forward along the neck band to a point adjacent to the lapels 13 and 14.

Directing attention to Figs. 3, 4 and 5, a hookless fastener such as described in U. S. Letters Patent No. 1,219,881 to Sundback, is attached to the back of the collar near the lower edge, as clearly shown in Fig. 3. Stringers 15 and 16 are attached at one edge 17 to the underside of the collar at a point sufficiently distant from the lower edge thereof to completely conceal the stringer and locking members. Locking members 18 are attached to the lower free edge of each stringer along the edge thereof. The free ends of the stringers are attached to the lower corners 19 and 20 of the collar, the stringers extending inwardly along the lower edge and converging upwardly near the center thereof as clearly shown in Fig. 4. A sliding cam 21, having a Y-shaped channel serves to engage the locking members of the two stringers when it is drawn outward from the position shown in Fig. 4 or disengage them when drawn in the opposite direction.

The operation of this device is clearly set forth in the above mentioned patent, but I do not intend to restrict myself to fasteners made in accordance with this patent, since any fastener having a pair of stringers carrying locking members operable by cam means may be used. It will be evident that when the collar is raised upward and the sliding cam 21 drawn along the stringers the latter will be drawn together.

drawing the two edges of the collar together to bring the latter into a hood shape. The upwardly converging portions 22 and 23 of the stringers serve to form the crowned tip 5 portion 24 of the hood, the edge of the collar at the center 25 folding inward to permit this adjustment.

Two purposes are served by fastening the stringer to the collar at a distance from the 10 lower edge. When the collar is in its normal lower position the fastener is in this manner completely concealed from view. On the other hand, when the fastener is closed the edges 26 and 27 of the collar are brought in 15 contact, completely covering the fastener from the interior of the hood thereby effectively preventing the hair from becoming caught or tangled in the portions of the fastener.

20 When the collar is brought into its raised position and the fastener closed it will be found convenient to raise the lapels 13 and 14 closely about the throat as shown in Fig. 1 whereby the front of the hood is brought 25 snugly about the face and under the skin, completely protecting the head and neck from the action of the elements, the left side 28 of the collar covering the left side of the head and neck, the right side 29 of the collar 30 covering the right side of the head and neck.

When the collar lies in its normal lower position it presents the neat and trim appearance of an ordinary sailor collar and protects the shoulders from the elements.

35 When the collar is raised to the elevated position to form the hood, a neat and shapely hood of ample size is formed. It will be seen that the collar may be raised to this position and the fasteners secured in a very convenient manner. No buttoning or hooking is 40 required. The sliding cam need only be grasped by the hand and drawn forward, a simple and easy operation which may be performed by the wearer with the coat in 45 position.

While I have thus described and illustrated in the particular embodiment of my invention I am aware that numerous changes may be made therein and I do not wish to 50 be limited except as required by the prior art and by the spirit and scope of the appended claim in which—

I claim:

55 A garment of the character described having a collar of inelastic material attached thereto at the neck, and a fastener comprising stringers attached to the underside of the collar and spaced from the lower edge extending from the lower corners thereof to 60 the center and meeting thereat in upwardly curved relation, locking members attached to said stringers, and a sliding cam actuating said locking members, to draw the lower edge of the collar together in the form of a hood 65 having a smooth outer surface, said collar ex-

tending forward along the neck of the coat to the lapels and extending outward therefrom being of sufficient width to extend upward over the head when raised, whereby the sliding cam may be drawn along the stringers folding the lower edge of the collar together to form a hood, the outer surface of the collar becoming the inner surface of the hood.

In witness of the foregoing I affix my sig- 75 nature.

ALFRED F. SCHRUP.
